UNITED STATES PATENT OFFICE.

JOHN DESMOND, OF TOLEDO, ASSIGNOR OF TWO-THIRDS, BY MESNE
ASSIGNMENTS, TO JOHN V. KENNEDY, OF CLEVELAND, OHIO.

STEAM-INJECTOR.

SPECIFICATION forming part of Letters Patent No. 330,682, dated November 17, 1885.

Application filed October 21, 1884. Serial No. 146,105. (Model.)

To all whom it may concern:

Be it known that I, JOHN DESMOND, a citizen of the United States of America, residing at Toledo, in the county of Lucas and State of Ohio, have invented certain new and useful 5 Improvements in Steam-Injectors, of which the following is a specification, reference being had therein to the accompanying drawings.

My improvement in steam-injectors consists 10 in the novel arrangement of its chambers connected by tubes and valves, in the peculiar construction of the valves and slide-lever for operating them, and in the combination and arrangement of the parts, substantially as 15 hereinafter more fully shown and described.

In the accompanying drawings, Figure 1 is a longitudinal sectional elevation, Figs. 2, 3, 4, and 5 are detail views, and Fig. 6 is a side elevation, of my invention.

20 In carrying out my invention I cast integral the metallic chamber A, comprising several partitioned-off compartments, the steam-nozzle B, the water-supply nozzle C, the water-outlet nozzle D, and the overflow-pipe E, and 25 construct the valve-seat F with apertures a and b.

The valve F', a cross-section of which is shown in Fig. 3, consists of the metallic slide d, conformed to the interior contour of the 30 valve-seat, and having recess e, for reception of tongue f of journal f', the metallic slide d being caused to register as a valve with the steam-port g and apertures a and b (see Fig. 1) by means of said journal f', actuated 35 by means of the slide-lever G, through which it projects. The journal f' is provided with the shoulder f³, (see Fig. 5,) which is adapted to a coincident recess, f⁴, in its valve-chamber, and is also provided with a corresponding 40 shoulder, f⁵, which, in conjunction with the screw-cap f⁶, retains the journal actuating the valve mechanism in its precise position therein.

The slide-lever G is constructed in sections, 45 the handle-section being jointed to the longitudinally-slotted section h by means of pin h', having an enlarged head projected through the guide-bar h² of the slotted section h, the pin h' being rigidly connected to the handle- 50 section of the slide-lever. The slotted con-

nection h' of the slide-lever has rigidly secured thereto the valve-rod H, having integral therewith the valve H', which is adapted as to size to fit the valve-seat of valve-chamber H³, and is provided with the transverse aperture H', which is designed to register with the ingress-port i, the egress-port j, and the overflow-pipe E of the valve-chamber H³. 55

The screw-cap I, which rotates freely on the valve-rod H, which projects through a central orifice therein, is threaded at I', and adapted to a coincident female screw provided in the interior part of valve-chamber H³. The screw-cap I is provided with a recess and a shoulder at I², for reception of spiral spring I³, which is designed to hold the screw-cap tightly against the hollow cap I⁴ of the slotted section h of the slide-lever G, and thus to prevent any leakage at that point, the hollow cap I⁴ and valve-rod H being rigidly secured together. 60 65 70

The operation is as follows: The valve d is caused to register with the steam-port a, thus admitting steam from the steam-supply pipe through nozzle B and port g, which finds outlet through steam-port b into chamber K, which is closed by screw-cap K', and which chamber has a threaded orifice provided in its dividing-wall K², wherein tube K³, having male screw K⁴ and screw-driver slot K⁵, is inserted, the screw-driver slot K⁵ being designed to enable it to be tightly screwed into the threaded orifice. Steam having been first admitted, as aforesaid, thereupon simultaneously with the opening of steam-port g and 75 closing of the port b, the slide-valve H' is caused to close the overflow-pipe E, and hence the steam forces water flowing from a conduit connected with a well through nozzle C and tube L into chamber M, and thence through 80 aperture i into valve-chamber H³, and the water thereupon passes through aperture j and ascends to valve-chamber F, whereupon the steam-valve d is caused to close the outlet-port b and open the outlet-port a, when the 85 water is forced through tube N provided in the partition-wall N', from thence into chamber O, and from thence through tube P into the outlet-nozzle D, having suitable connection with the steam-boiler. 90 95 100

Having thus fully described my invention, what I claim and desire to secure by Letters Patent, is—

1. A steam-injector consisting of metallic chamber A, comprising inclosed compartments connected by tubes, valves d and H', and slide-lever G, substantially as shown and described.
2. The combination of chamber A, having compartments, connecting-tubes, nozzles, and an overflow-pipe, with valves F and H', operated by a slide-lever, G, substantially as shown, and for the purpose described.
3. The combination of the valve H', spiral spring I³, and slide-lever G, having cap I⁴, for making a tight joint, substantially as shown and described.

4. A steam-injector operated by a slide-lever in connection with valves and compartments connected by tubes, said lever consisting of two sections, one of said sections carrying a pin entering a slot of the other section, substantially as shown, and for the purpose described. 20

In testimony whereof I affix my signature in presence of two witnesses.

JOHN DESMOND.
